FABRIC

Clarence E. Pink, Cambridge, Md.

Application April 26, 1934, Serial No. 722,554

8 Claims. (Cl. 245—6)

This invention relates to fabrics of the woven coil wire type and has for the primary object the provision of means located within the fabric and extending from opposite edges thereof inwardly of said fabric and terminating within the latter to provide the fabric with selvages adapted to prevent the fabric from tearing or becoming out of shape and which will not affect the flexibility of the fabric or materially increase the cost of manufacture thereof.

Another object of this invention is the provision of coil strands of the same formation as the coil strands of the fabric and screwed into or interwoven with the strands of said fabric from opposite edges of the latter inwardly of the fabric to provide reinforcing selvages to the fabric with means also cooperating therewith to strengthen the fabric at its selvages for maintaining the reinforcing strands in the same plane with the strands of the fabric so that the reinforcing strands will not drop outwardly of the strands of the fabric during the use of the latter.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a fragmentary plan view illustrating a fabric constructed in accordance with my invention.

Figure 2 is a fragmentary plan view showing the reinforcing strands woven with one another and with the strands of the fabric.

Figure 3 is a fragmentary sectional view taken on the line 3—3 of Figure 1.

Figure 4 is a similar view taken on the line 4—4 of Figure 1.

Figure 5 is a perspective view illustrating one of the reinforcing elements.

Referring in detail to the drawing, the numeral 10 indicates a woven wire fabric composed of coiled wire strands 11 woven or screwed one into the other. The strands 11 may be of either right hand coiled formation or left hand coiled formation and the ends of said strands are suitably secured together in pairs either by welding, knuckling or in any other manner well known in this art. A fabric thus constructed is useful for many purposes and primarily for the making of endless conveyor belts. The strands 11 of the fabric extend transversely of the belt when the fabric is employed for this purpose and if desired and at spaced intervals of the fabric, reinforcing rods 12 may be extended through the convolutions of pairs of the strands, as illustrated in Figure 1, by a single rod having its ends secured to the ends of the respective pair of strands,

for the purpose of reinforcing the fabric and aiding in preventing the fabric from shrinking or spreading out of shape due to excessive strains or loads thereon.

To prevent tearing and to strengthen the fabric my invention is employed and consists of selvages for the fabric, as clearly shown in Figure 1. The selvages are constructed from coiled wire strands 14 of the same formation as the strands 11 and the strands 14 of each selvage are woven or screwed one into another and also into the strands 11. The strands 14 are approximately of the same length and much shorter than the strands 11 so that the inner ends of the strands 14 terminate within the fabric and also within the convolutions of the strands 11. The outer ends of the strands 14 are connected in pairs by welding or knuckling. The outer ends of the strands 14 terminate in alignment with the ends of the strands 11. The strands 14 afford maximum strength to the fabric where employed therein and do not prevent such portions of the fabric which have the strands woven therein from flexing. The strands 14 due to their connections in pairs will be prevented from working out of the fabric or transversely of the fabric to any appreciable extent.

Elements 15 of substantially hairpin shape are passed into the convolutions of the strands 11 and 14 at the selvages of the fabric. Each element is composed of connected parallel leg portions and one leg portion lies in the convolutions of the reinforcing strand 14 and the other leg portion lies in the convolutions of the fabric strand 11 interwoven with the strand 14 so that the strands 11 and 14 will be maintained in the same plane, obviating the reinforcing strands 14 from dropping out or moving laterally of the strands 10 during the use of the fabric and especially when employed in the construction of conveyor belts, where the strands 14 would have a tendency to drop out of the strands 11 and present unevenness to the opposite faces of the belt. The elements 15 being constructed from flattened material, as shown in Figure 3, more readily maintain the strands 11 and 14 in the same horizontal plane as said elements contact with opposite sides of the convolutions of the strands. The elements are inserted in the convolutions of the strands before the connecting of the ends of the strands and are prevented from moving out of the fabric by the connected ends of the strands. The ends of the elements 15 terminate in the fabric in substantial alignment with the inner ends of the strands 14. However, said elements may be made to extend further into the fabric and would then reinforce the strands 11 of said fabric to a greater extent.

The connected ends of the strands 11 and 14 and the connecting portions of the elements 15 form wear resisting edges to the selvages capable

of effectively resisting wear and also materially preventing the fabric from tearing at the edges when the fabric is employed in conveyor belts and which during use crowd or bear against guides 5 and rollers placing thereon forces acting to wear or tear the belt.

Having described the invention, I claim:

1. In a metallic fabric, coiled wire strands of the same formation woven one into the other to form the fabric, and coiled strands of the same 10 formation as the first-named strands woven into the latter and into one another to reinforce portions of the fabric and provide selvages to the latter, said second-named strands arranged in 15 pairs with their ends connected to one another.

2. In a metallic fabric, coiled wire strands of the same formation woven one into the other to form the fabric, and coiled strands of the same 20 formation as the first-named strands and of a shorter length than the latter and woven therein and into one another to form selvages for the fabric, said second-named strands extending inwardly 25 from the opposite edges of the fabric and terminating within the fabric and within the convolutions of the first-named strands, said first-named strands having the ends thereof connected to group the first-named strands in pairs and the second-named strands having their outer ends 30 connected to group said second-named strands in pairs.

3. In a metallic fabric, coiled wire strands of the same formation woven one into the other to form the fabric, and coiled strands of the same 35 formation as the first-named strands woven into the latter and into one another to reinforce portions of the fabric and provide selvages to the latter, and means positioned in the convolutions of the strands and within the selvages to reinforce the latter and to prevent the second-named 40 strands from moving outwardly of the first-named strands.

4. In a metallic fabric, coiled wire strands of the same formation woven one into the other to form the fabric, coiled strands of the same 45 formation as the first-named strands woven into the latter and into one another to reinforce portions of the fabric and provide selvages to the latter, and elements extending into the convolutions of said strands and contacting with opposite walls of the 50 convolutions to reinforce the selvages and prevent the second-named strands from moving outwardly of the first-named strands and each composed of connected parallel portions.

5. In a metallic fabric, coiled wire strands of the same formation woven one into the other to form the fabric, coiled strands of the same formation as the first-named strands and of a shorter 55 length than the latter and woven therein and into one another to form selvages for the fabric, said second-named strands extending inwardly from opposite edges of the fabric and terminating within the fabric and within the convolutions of the first-named strands, said first-named strands having the ends thereof connected to group the first-named strands in pairs and the second-named strands having their outer ends 60 connected to group the second-named strands in pairs, reinforcing elements for the selvages each composed of parallel connected leg portions, one portion of each element extending into the convolutions of a second-named strand and the other leg portion extending into one of the first-named strands, the connecting portion of said leg portions lying inwardly of the connected ends of the strands to prevent the elements from moving outwardly of the fabric, said leg portions terminating within the fabric in substantial alignment with the inner ends of the second-named 65 strands and each element composed of flattened material so as to contact with opposite walls of the convolutions of said strands.

leg portion extending into one of the first-named strands.

6. In a metallic fabric, coiled wire strands of the same formation woven one into the other to form the fabric, coiled strands of the same formation as the first-named strands and of a shorter length than the latter and woven therein and into one another to form selvages for the fabric, said second-named strands extending inwardly from opposite edges of the fabric and terminating within the fabric and within the convolutions of the first-named strands, said first-named strands having the ends thereof connected to group the first-named strands in pairs and the second-named strands having their outer ends 10 connected to group the second-named strands in pairs, reinforcing elements for the selvages each composed of parallel connected leg portions, one portion of each element extending into the convolutions of a second-named strand and the other leg portion extending into one of the first-named strands, the connecting portion of said leg portions lying inwardly of the connected ends of the strands to prevent the elements from moving outwardly of the fabric. 15

7. In a metallic fabric, coiled wire strands of the same formation woven one into the other to form the fabric, coiled strands of the same formation as the first-named strands and of a shorter length than the latter and woven therein and 20 into one another to form selvages for the fabric, said second-named strands extending inwardly from opposite edges of the fabric and terminating within the fabric and within the convolutions of the first-named strands, said first-named strands having the ends thereof connected to group the first-named strands in pairs and the second-named strands having their outer ends 25 connected to group the second-named strands in pairs, reinforcing elements for the selvages each composed of parallel connected leg portions, one portion of each element extending into the convolutions of a second-named strand and the other leg portion extending into one of the first-named strands, the connecting portion of said leg portions lying inwardly of the connected ends of the strands to prevent the elements from moving outwardly of the fabric. 30

8. In a metallic fabric, coiled wire strands of the same formation woven one into the other to form the fabric, and coiled strands of the same formation as the first-named strands and of a shorter length than the latter and woven therein and into one another to form selvages for the fabric, said second-named strands extending inwardly from the opposite edges of the fabric and terminating within the fabric and within the convolutions of the first-named strands, said first-named strands having the ends thereof connected to group the first-named strands in pairs and the second-named strands having their outer ends 35 connected to group said second-named strands in pairs, and having their inner ends connected and arranged in the convolutions of the first-named strands. 40

CLARENCE E. PINK.
